UNITED STATES PATENT OFFICE.

EDGAR LEE FLOWERS, OF HICKORY, NORTH CAROLINA, ASSIGNOR TO HOME CANNER COMPANY, OF HICKORY, NORTH CAROLINA.

CANNING APPARATUS.

1,109,673.

Specification of Letters Patent.

Patented Sept. 8, 1914.

Application filed September 13, 1913. Serial No. 789,711.

REISSUED.

To all whom it may concern.

Be it known that I, EDGAR L. FLOWERS, a citizen of the United States, residing at Hickory, in the county of Catawba, State of North Carolina, have invented certain new and useful Improvements in Canning Apparatus; and I do hereby declare the following to be a full, clear, and exact description of the invention, such as will enable others skilled in the art to which it appertains to make and use the same.

The present invention is directed to canning apparatus and has for its object to construct an apparatus of this character, which is extremely simple in construction, efficient in operation, and one which may be manufactured at a minimum cost.

With this and other objects in view, this invention resides in the novel features of construction, formation, combination and arrangement of parts to be hereinafter more fully described, claimed and illustrated in the accompanying drawing, in which:—

Figure 1 is a side elevation of the device. Fig. 2 is a longitudinal sectional view. Fig. 3 is a sectional view on line 3—3 of Fig. 1. Fig. 4 is a similar view on line 4—4 of Fig.

1. Fig. 5 is a front view. Fig. 6 is a sectional view on line 6—6 of Fig. 2.

30 Referring to the drawing, the numeral 1 designates the boiler, which is preferably rectangular in shape, and comprises a bottom 2, sides 3, ends 4 and an open top 5 which is closed by the cover 6. The forward 35 end of the boiler 1 is provided with a transverse partition 7, which produces a blanching or scalding chamber 8, the same being closed at its upper end by the cover 6.

The furnace 9 is rectangular in cross section, and comprises a bottom 10, sides 11 and a closed end 12, the open end 13 of which abuts against the rear wall 4 and registers with the door opening 14, so that the removable grate 15 can be supplied with fuel when necessary, or removed when desired, said door opening being closed by the hinged

door 16, which is provided with a draft regulator 17. The furnace 9 is supported within the boiler by legs 18, and is of such dimensions that its top 19, sides 11, bottom 10 and closed end 12 are spaced from the interior surface of the boiler 1, so that when water is in the boiler, the same may circulate freely around the furnace and becomes thoroughly heated.

55 Leading from the forward end of the furnace 10, and passing through the chamber 8 is the curved section 20 of the flue 21, which extends rearwardly through the boiler. The products of combustion pass through the flue 60 to the chimney 22, it being obvious that as the products pass therethrough the water in said chamber and boiler will be thoroughly heated. Mounted upon the top 19 of the furnace is a wooden frame 23, and upon which 65 the can baskets 24 are placed during the operation of the apparatus.

To one side of the boiler 1 is connected a faucet 25, which serves to allow water to be drawn from the boiler when it is desired. A 70 faucet 26 is provided and communicates with the chamber 8 so that water may be drawn therefrom when desired.

In use the boiler is filled with water to a point slightly above the top 19 of the furnace, so that the baskets 24 will be submerged, and the cans contained therein subjected to the action of the hot water.

75 The partition 7 is provided with a valve 27, which is operable to permit water to pass 80 from the chamber 8 to the boiler 1 should the water therein fall below the predetermined level.

What is claimed is:—

85 A canning apparatus comprising a boiler, a chamber formed in one end of the boiler, a cover for the upper end of the boiler, a furnace mounted in the boiler and having its bottom, sides and one end spaced from the interior surface of the boiler, the other end 90 of said furnace being open, a door opening formed in one end of the boiler, and in reg-

istry with the open end of the furnace, a door for closing the opening, a horizontally disposed flue leading from one end of the furnace and spaced therefrom and one side of the boiler, said flue passing through the chamber and boiler to permit products of combustion to pass from the furnace and to heat the liquid in said chamber and boiler

and a frame removably supported upon the furnace and flue.

In testimony whereof, I affix my signature, in the presence of two witnesses.

EDGAR LEE FLOWERS.
